GESELLSCHAFT, WERNERWERK, OF SIEMENSSTADT, NEAR BERLIN, GERMANY

TELEPHONE SYSTEM

Application filed September 9, 1929, Serial No. 391,299, and in Germany October 25, 1928.

The invention relates to the positioning of non-decimal switches in communication systems; it consists in that the impulse senders have decimal positioning members and are 5 provided with devices, which send out in one impulse train a number of impulses equal to the number of the wanted connection.

One method of carrying out the invention is shown by way of example in the drawing. 10 The invention is not limited to this example. Only those circuit details are shown that are required to understand the invention.

The drawing shows at Zg a number sender and at W a diagrammatically shown switch; 15 whose stepping means—not shown in the drawing—is operated by the impulses transmitted from the number sender. The number sender Zg comprises a 50-point rotary switch similar to the rotary lineswitch well known in automatic telephony and consisting 20 of a rotary operating magnet D 1 and three contact banks wiped over by the wipers a , b , and c . This number sender is controlled by ordinary strips of 10 keys each. Of the units 25 strip only the keys E 1, E 2 and E 0 are shown diagrammatically and of the tens key strip only the keys Z 0, Z 1, and Z 2 are shown. On pressing any units key, a starting key E is actuated at the same time.

30 The lines coming from the key strips are connected in the following manner to the contact banks of the number sender. In the segment wiped over by the switch wiper b the contacts 1-9, 10-19, etc., are interconnected.

35 The lines coming from the tens keys go to these individual contact groups; thus, for example, the line over which battery is applied by the key Z 0 goes to the contact group 1-9; Z 1 to contacts group 10-19, etc. At the

40 segment, which is wiped over by the wiper a , the key E 1 applies earth to the contacts 1, 11, 21, etc. Similarly, the other keys apply earth to their corresponding contacts. The method of operating the number sender is as

45 follows: By pressing the key A the operator can ascertain whether the number sender is in the normal position so that it can be used. The free lamp FL is then lighted in the following circuit: earth, battery, lamp FL , wipers a and b of the number sender in posi-

tion O , key A , earth. If a units and tens key be now pressed, the starting key E is operated at the same time as before described. The latter closes the following circuit for the relays R and An : earth, battery, winding of relays An and R , wiper c in position O , key E , earth. Relay An at its contact 10 an prepares the sending circuit going to the switch W . Relay R is operated and closes its contacts 2 r and 3 r . Over contact 2 r , the relay X is energized as follows: earth, battery, resistance, winding of relay X , contact 2 r , earth. Relay X closes its contacts 3 x and 4 x and opens contact 5 x . While relay X locks itself over contact 3 x , the contact 4 x closes the following circuit for the rotary magnet D 1: earth, battery, winding of the rotary magnet D 1, contact 4 x , earth. The contact 5 x will be mentioned later in conjunction with the circuit of relay P . On operating, the rotary 55 magnet D 1 short circuits the relay R over contact 12 d 1 and this relay falls back. Thereby the contact 1 r again short circuits the relay X and it falls back. Contact 4 x 60 opens the circuit of the rotary magnet D 1, 65 which deenergizes and advances the wipers to the next set of bank contacts and at contact 12 d 1 removes the short circuit from relay R , which can then be operated again. An impulse is sent to the switch W each time 70 the relay R operates. When the wipers a and b of the number sender simultaneously wipe over a contact earthed over the units key and one of the tens group, to which battery has 75 been applied over a tens key, the relay P is operated in the following circuit: earth, battery, winding of relay P , contact 5 x , pressed tens key, wiper b , wiper a , pressed units key, earth. This circuit is not closed until contact 80 5 x has been closed, that is to say, until relay X has fallen back, so that now the last of the required impulses has been sent over the line to switch W . Relay P closes its contact 15 p to lock itself in the following circuit: earth, battery, winding of relay P , contact 15 p , 85 wiper c , earthed contact bank of wiper c . Relay P at contact 16 p also opens the lead to switch W , thereby stopping the impulse transmission. Relay P locks itself until the 90 number sender is again in its normal position. 95 100

By then the contact E, which was closed when the units key was pressed, is again open.

What is claimed is:

1. In a register sender comprising a rotary switch having two wipers and arranged to transmit an impulse each time the wipers are advanced one step, a set of bank contacts for each of said wipers, means for placing a variable marking on certain bank contacts of each set, and means effective when said wipers simultaneously engage marked bank contacts for stopping the transmission of impulses.
2. In a register sender, a rotary switch having two wipers each arranged to wipe over a set of bank contacts, means for marking certain of the bank contacts of each set, an impulsing circuit momentarily closed at each step of said switch, and means effective when said wipers simultaneously engage marked bank contacts for opening said impulsing circuit and maintaining said circuit open until said switch has returned to normal.
3. In a register sender, a rotary switch having a plurality of wipers each arranged to wipe over a set of bank contacts, a group of keys associated with each set of banks for marking said contacts in accordance with the number of impulses to be transmitted, means responsive to the operation of said switch for transmitting a series of impulses whose length is limited only by the number of contacts in each of said banks, and means controlled over two of said wipers in series for stopping the transmission of impulses at any predetermined point as indicated by the marking of the bank contacts.
4. In an operator's sender, a set of units keys and a set of tens keys, a counting switch having a units wiper and a tens wiper each arranged to wipe over a set of bank contacts connected to said units and tens keys, respectively, and a testing circuit including said wipers in series and effective when said wipers simultaneously engage bank contacts associated with depressed units and tens keys.
5. In a register sender, a group of units keys and a group of tens keys for setting up the number of impulses to be transmitted in a single series, a counting switch having a units wiper and a tens wiper whose banks are connected to said units keys and said tens keys, respectively, a test relay for stopping the transmission of impulses, and a circuit for said relay closed when said wipers simultaneously engage bank contacts associated with depressed units and tens keys.
6. In a register sender, tens and units registers, an impulse sender, and a counting switch controlled by both registers while said impulse sender is transmitting a single series of impulses.
7. In a register sender, two registers, a counting switch controlled by both of said registers, means controlled by said counting switch for transmitting a single series of impulses whose length is governed by the setting of said two registers, and two wipers on said counting switch cooperating with said registers, respectively, for determining the length of said series.
8. In combination, a counting switch having a plurality of wipers and a set of bank contacts associated with each wiper, registering means for temporarily marking certain bank contacts in each set, means for operating said counting switch, and means responsive to the operation of said switch for transmitting a single series of impulses whose length is governed by the marking on said bank contacts.
9. In a register sender, means for registering the two digits of a two digit number, an impulse sender, and means controlled by said registering means for causing said impulse sender to transmit a series of impulses equal in number to the numerical value of the two digit number.
10. In combination, registering apparatus, a plurality of control conductors extending from said apparatus to a testing device, a sending device associated with said testing device, means for operating said sending device, and means for operating said testing device to progressively test said conductors in pairs during the operation of said sending device.
11. In combination, a sending device including a rotary switch, a plurality of control conductors terminating in the banks of said switch, a plurality of keys for placing marking potentials on said conductors, and means for progressively operating said switch to test said conductors in pairs for marking potentials.
12. In a register sender, a register comprising a plurality of registering devices having a pair of contacts each, each device being operable to close its contact pair, means for operating said devices in any one of more combinations or orders than there are devices, and an impulse sender operable to send a series of impulses and to test said contact pairs in said combinations as the impulses are being transmitted, there being a different number of impulses assigned to each combination.
13. In a register sender, a register comprising a plurality of registering devices having a pair of contacts each, each device being operable to close its contact pair, means for operating said devices in any one of more combinations or order than there are devices, an impulse sender operable to send a series of impulses and to test said contact pairs in said combinations as the impulses are being transmitted, there being a different number of impulses assigned to each combination, and means for terminating the impulse transmission when the test made indicates that

the impulses transmitted correspond in number to the combination registered.

14. In a register sender, a register comprising separately-operable registering devices, means for separately operating said registering devices in any one of more combinations or orders than there are devices, a sender, means for operating said sender to transmit a series of impulses, and means including separate connections to said sender from said registering devices, respectively, for controlling the number of impulses in the series in accordance with the instant combination or order set up on said register so that the number of impulses contained in said series distinguishes any registered one of said combinations or orders from any other one of said combinations or orders.

15
20 In witness whereof, I hereunto subscribe my name this 15th day of August, A. D. 1929.
